UNITED STATES PATENT OFFICE.

HENRY J. GIESEKE, OF ELIZABETH, NEW JERSEY, ASSIGNOR TO MRS. KATHERINE GOODYEAR, OF NEW YORK, N. Y.

HYDROCARBON BURNER.

Application filed May 18, 1923. Serial No. 639,932.

This invention relates to burners for burning vaporized hydrocarbon fuel such as that derived from the vaporization of crude oil, kerosene and other similar hydrocarbons.

In burners of this type, the fuel is vaporized by the passage of the same through a preheater before it reaches the openings or jets of the burner. This preheater, ordinarily during the operation of the burner after it has started, is heated from the burning vapor issuing from the jets of the burner. In order to start the burner into operation, one or more starting cups are ordinarily provided into which a certain quantity of the liquid employed in the burner or some other more easily ignited fuel is poured and the fuel contained in these cups is lighted to heat up the preheater sufficiently to vaporize the fuel. The starting of the burner in this manner involves some labor and trouble and the heating up of the preheater is a slow operation since the liquid in the starting cups burns with a flame of comparatively low temperature.

One object of the present invention is to produce a burner mechanism for burning vapor produced from hydrocarbon fuels in which the burner may be started more easily and quickly than in burners heretofore devised. With this object in view, a feature of the invention consists in the provision of a separate starting burner and devices separate from the main fuel supplying devices for supplying fluid fuel thereto.

As is well known to those skilled in the art, it is desirable to force the hydrocarbon fuel to the burner under pressure. This enables the fuel tank to be placed in any convenient position with relation to the burner and also insures a constant uniform supply of fuel under all conditions.

Another object of the present invention is to provide burners of the class described with improved means for producing the requisite pressure upon the fuel in the main supply tank to deliver the fuel under pressure to the burner.

With the latter object in view, a feature of the invention consists in the provision of means for delivering to the main fuel supply tank a constant supply of gas under pressure. In the preferred form of the invention, the starting burner is constructed

and arranged to burn gaseous fuel, and this burner is supplied with gas and gas is also delivered from the main fuel supply tank to produce the required pressure from the same source.

The invention also comprises certain other novel and improved features of construction and combinations of parts herein-after described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings, Fig. 1 is a view partly in front elevation and partly in section of a burner mechanism embodying the invention, and

Fig. 2 is a detail view in side elevation; illustrating certain of the parts shown in Fig. 1.

In the form of the invention shown in the drawings, the burner for burning vaporized hydrocarbon fuel comprises a hollow ring-shaped member indicated at 2 provided with a series of openings 4 through which jets of gaseous mixtures are discharged and arranged to be supplied with a gaseous mixture through an inlet pipe 6. Before the vapor enters the inlet pipe, a certain quantity of air is mixed therewith to form a mixture which will burn with great heat. The vaporized oil enters the inlet pipe 6 through a jet 8 and air enters the pipe through one or more openings 10 arranged about the jet 8, the air being drawn through these openings by the venturi effect produced at said jet. Before being delivered to the jet 8, the hydrocarbon liquid fuel is vaporized in a suitable preheater. This preheater comprises a chambered ring indicated at 12, which is connected with the jet 8 by means of suitable piping 14. The flow of the vapor from the ring 12 into the inlet pipe 6 is controlled by means of a valve 16. The preheater ring 12 is supplied with hydrocarbon liquid fuel through a series of pipes 18 from a main supply tank 20. The fuel from the supply tank 20 is delivered as a liquid through the pipes 18 to the preheater 12. Here it is vaporized by the high temperature of the preheater and is then deliv-

ered through the pipes 14 to the jet 8 where it is mixed with the proper quantity of air and then passes through the supply pipe 6 to the burner.

5 The valve 16 is mounted on the inner end of a rod 21 threaded into a part of the piping 14 and carrying at its outer end a hand-wheel 23 for turning the same to adjust the valve.

10 The preheater 12 is arranged to be heated to start the main burner by means of a small acetylene burner 22 which is cut off after the main burner is started, the pre-heater then being heated from the main 15 burner. The acetylene burner 22 is supplied with gas through a series of pipes 24 from a tank 26. Air is mixed with the acetylene gas before it reaches the burner to form a highly combustible mixture, this 20 air entering one of the pipes 24 leading directly to the burner through a series of openings 28 in the pipe. The flow of gas through the pipes 24 is arranged to be controlled by cocks 30 and 32. In starting 25 the burner, the cocks are adjusted to supply acetylene gas to the burner and after the burner is well started, the cock 30 is shut off, the preheater 12 then being heated by the flame from jets 34 formed in the main 30 burner 2.

With this construction, the burner may be started quickly without any trouble and the heating up of the burner to a temperature such that it will operate efficiently is 35 accomplished in a very short time.

In the present form of the invention, the acetylene gas developed in the generator 26 is utilized to supply pressure to the fuel contained in the supply tank 20, thereby 40 insuring a constant uniform supply of fuel to the burner under all conditions. To this end a series of pipes 36 are provided to connect one of the pipes 24 with the upper end of the supply tank 20. The tank 20 is 45 provided with a filling tube 38 secured to the top of the tank and extending therefrom to a point close to the bottom of the tank and is clearly shown in Fig. 1. The tank is also provided with a discharge pipe 40 50 connected with one of the pipes 18. Thus when the tank 20 is filled or partially filled with liquid fuel, the pressure of the gas in the upper part of the tank above the fuel assisted by the weight 55 of the fuel will force the fuel outwardly through the discharge pipe 40 and through the pipes 18 to the burner. In order that the acetylene in the tank may not be discharged through the filling tube 38, 60 the discharge pipe 40 is arranged to extend within the tank and its upper end is located somewhat above the lower end of the filling tube 38. To prevent the acetylene from 65 passing outwardly through the discharge pipe 40 when the supply of fuel in the tank

is low, a float 42 is provided for then closing the discharge pipe.

The upper end of the filling tube 38 is closed by a cap 44. The pipe 36 is provided with a cut-off cock 46 and the tank 20 is provided with a vent pipe 48 which is adapted to be closed by a cut-off cock 50. The cut-off cocks 46 and 50 are preferably connected together so that they may be operated in unison, the cock 50 being closed 75 when the cock 46 is opened and vice versa. As shown, the cocks are provided with a common operating handle 52. This handle is arranged so that, when the main burner is in operation, the cock 46 then being 80 opened and the cock 50 closed, the handle is turned down so that it rests on top of the cap 44 which then closes the filling tube 38. When it is desired to fill the tank 20, before the cap 44 may be unscrewed, the handle 52 must be lifted thereby closing the cock 46 and opening the vent cock 50. Thus the cap 44 cannot be removed while the connection between the fuel tank 20 and the acetylene tank 26 is opened, and the vent 85 cock 50 is always closed at this time. Thus any escape of the acetylene gas except that which passes off through the vent tube 48 when the fuel tank is being filled is absolutely prevented. 95

The acetylene tank 26 is supplied with carbide from a reservoir 54 mounted on a neck formed at the upper end of the tank, which reservoir is provided at its lower end with a conical portion having an opening 100 56 controlled by an automatic valve 58. This valve is attached to the lower end of a valve rod 59, the upper end of which rod is secured to a diaphragm 60 secured at its margin to the wall of the reservoir. The 105 diaphragm 60 is preferably made of sheet rubber and carries a weight 62 resting on a block 63 secured to the central part of the diaphragm which tends to depress the diaphragm and open the valve. The diaphragm 110 is held up against the action of the weight 62 by the pressure of the gas developed in the tank 26 and passing therefrom upwardly through the opening 56 into the reservoir. With this construction, as the 115 pressure of the gas within the tank 26 decreases, the valve 58 opens to supply more carbide to the tank. The increase in the feed of the carbide causes an increase in the development of gas in the tank 26 and the gas then raises the diaphragm 60, thereby partially closing the valve 58 to diminish the supply of carbide fed to the tank. The feed of the carbide to the tank is thus controlled 120 automatically and tends to maintain a substantially uniform pressure in the tank. It is to be understood, however, that the valve 58 is so constructed that it never forms a gas-tight engagement with its seat. 125

Having explained the nature and object 130

of the invention and having specifically described the mechanism embodying the invention in its preferred form, what is claimed is—

- 5 1. In a fuel burner system, an acetylene gas generator, a liquid fuel tank, a pipe connecting the acetylene gas generator with the fuel tank, a liquid fuel burner, a pipe leading from the liquid fuel tank to the
10 liquid fuel burner, an acetylene gas burner, a branch pipe leading off from the pipe connecting the acetylene gas generator with the liquid fuel tank, said pipe supplying acetylene gas to the acetylene gas burner, and means in said pipe for cutting off the supply of gas to the acetylene gas burner, and separate means for cutting off the supply of acetylene gas to the liquid fuel tank.
15 2. In a fuel burner system, an acetylene gas generator, a liquid fuel tank, a pipe connecting the acetylene gas generator with the fuel tank, a liquid fuel burner, a pipe connecting the liquid fuel burner with the liquid fuel tank, an acetylene gas burner, a pipe leading from the
20 pipe connecting the acetylene generator to

the liquid fuel tank for supplying acetylene gas to the acetylene gas burner, means in the pipe connecting the acetylene gas generator with the liquid fuel tank for cutting off the supply of acetylene gas to both the liquid fuel tank and the acetylene burner, and separate means for cutting off the supply of acetylene gas to the acetylene gas burner independently of the liquid fuel tank. 30

3. A fuel burner system comprising a fuel retort, two burners arranged to heat said retort, an acetylene gas generator, a liquid fuel tank, means for supplying acetylene gas to one of said burners, means for supplying acetylene gas to the liquid fuel tank to feed the fuel contained therein to the retort, means connecting the retort with the other of said burners to supply vaporized fuel thereto, and means for cutting off the supply of acetylene gas from the acetylene gas burner without cutting off the supply of acetylene gas from the liquid fuel tank. 40

Signed at New York City, N. Y., this 7th day of May 1923.

HENRY J. GIESEKE.
